PROJECTILE

Latham Valentine Stewart Blacker,
Coldhayes, Liss, England

Application October 24, 1951, Serial No. 252,866

7 Claims. (Cl. 102—49)

1

This invention relates to that kind of projectile which is discharged from a barrelled weapon by an explosive charge and which has a tail joined to the head by a tube. To ensure accuracy when such a projectile is fired it is important that the gases produced by the explosive charge should be closely confined behind the projectile within the barrel, and therefore a gas check may advantageously be provided behind the tail to make a gas seal with the barrel.

When there is a gas check the force of the explosion is transmitted from the tail to the head. A substantial load is therefore applied to the tube connecting the head and tail, and to take this load the tube must be heavy. This in turn shifts the centre of gravity further aft than is desirable.

It is an object of the present invention to provide a projectile of this kind with a gas check and means for transmitting thrust from the gas check to the head independently of the tube connecting the head and tail.

It is another object to provide a projectile of this kind with a combined gas check and thrust transmitting assembly which is jettisoned in flight.

It is a further object to provide an explosive charge for propelling a gas check forcibly rearwards and so assisting the flight of the projectile.

It is yet another object so to construct a gas check assembly that when pressure is applied to the gas check the assembly moves forwards relatively to the projectile and imparts a forward blow to its head.

Essentially a projectile embodying the invention has a gas check behind the tail, a device constituting a strut within the tube for transmitting thrust from the gas check to the head, and an explosive charge within the tube for jettisoning the gas check and strut device from the projectile in flight. The strut relieves the tube of the thrust during discharge, and the jettisoning of the gas check and strut ensures that in flight the projectile will have low drag and a centre of gravity in a satisfactory position. The reaction of the explosion of the jettisoning charge assists the projectile in flight. The invention will be most clearly understood by reference to the accompanying drawings which show three projectiles embodying the invention. In these drawings—

Figure 1 is a longitudinal section of the rear part of a mortar bomb and cartridge;

Figure 2 is a longitudinal section of a bomb

2

and cartridge for breech-loading into a gun; and

Figure 3 is a longitudinal section of a further mortar bomb and cartridge.

The head 2 of the bomb shown in Figure 1 is of streamline form and contains an explosive charge. It is steadied in flight by a drum tail 8 connected to the head by a light tube 10.

Before firing, the bomb is fitted with a cartridge and gas check assembly. This includes a primary charge 12 which fires the bomb from a mortar and which is contained in a body 14 together with a primer 16. The gas check is constituted by a thin cup 20 which is expanded radially into contact with the barrel when the bomb is fired by the charge 12 and which bears against a thick flange 18 on the body.

The front of the body 14 is formed as a spigot which makes a tight push fit in the end of the tail tube 10 and rests against a cover 22 on the end of a thick walled tubular strut 24. This strut constitutes a thrust transmitting device, and it houses a secondary charge 25 for jettisoning the entire cartridge and gas check assembly and bears against the base of the head 2.

Initially the extreme diameter of the cup 20 is, like that of the head, slightly less than the internal diameter of the barrel of the mortar from which it is fired. Thus the bomb with the cartridge and gas check assembly will pass freely down the barrel. When the primary charge 12 is fired upon engagement of the primer 16 with a fixed firing pin, the cup 20 expands slightly and its trailing lip makes a seal with the barrel.

The thrust produced by the explosion of the primary charge is transmitted to the bomb through the flange 18, the body 14, the cover 22 and the strut 24. Thus no thrust is applied to the tail tube 10, which can be made just strong enough to carry the tail.

The explosion of the primary charge also drives forward a small cup 32 within the body 14. This cup carries a firing pin 34 which hits a primer in the cover 22 and so fires the secondary charge 25. Pressure builds up within the tail tube 10 and forces a lip 27 on the cover 22 radially outwards into sealing contact with the tail tube 10. Shortly after the bomb is clear of the mortar this pressure overcomes the declining propellant thrust resulting from the explosion of the primary charge and blows the cover 22 out of the tail tube, so jettisoning the gas check and also drawing with it the strut 24, which is held to the cover by a ring 23. The proportions of the primary explosive charge by which the projectile is discharged and the secondary charge

within the tube are such that immediately after being jettisoned the gas check has a velocity towards the weapon. In this way a considerable momentum is transferred from the gas check to the projectile without any addition to the recoil of the weapon, because the secondary jettisoning charge acts after the pressure and recoil resulting from the explosion of the primary charge have reached their peak. The drag of the gas check when it is travelling backwards is greater than when it is travelling forwards and so it does not return far along its path of discharge. By reason of this drag it may be propelled rearwardly with substantial energy without endangering the operator of the weapon, and in fact the rearward velocity of the gas check may be greater than that with which it leaves the barrel of the weapon. While the gas check 20 remains with the bomb during its first few feet of flight, air passing inside the drum tail can escape through a slot 36. Thus the drag at this stage is kept as low as possible.

The bomb shown in Figure 2 differs from that shown in Figure 1 in little except the proportions of its parts. The primary charge 38 is housed in a tube 43 which is surrounded by a cartridge case 42 and which is screwed onto the body 44 of the gas check. This screwed connection breaks on firing. The body 44 is elongated as a tubular spigot 46 which extends about half way up the tail tube 48. It thus forms part of the strut, and the remaining tubular part 50 is shorter than the strut 24 in Figure 1. A delay 52 is incorporated between the primer 54 and the secondary charge 56. This allows the bomb to move about a foot before pressure begins to build up within the forward part of the tube 48.

In the construction shown in Figure 2 the thrust is transmitted through the spigot tube 46 to the casing of the primer 54 and from this casing to the strut part 50 and thence to the head of the bomb.

In the bomb shown in Figure 3 a spigot 58 extending from a gas check 60 is initially located within a tail tube 62 by interengagement of shallow grooves 64 made in both the spigot 58 and the tube 62. In this position there is a space 65 between the front of the spigot and the casing 66 of a primer 68. When the primary charge 70 is fired the gas check is driven forwards relatively to the projectile and the spigot 58 imparts a blow to the casing 66 which is transmitted to the head 72 of the projectile by a strut composed of two conical parts 74 and 76. At the completion of this forward movement there is still a clearance between the gas check and the end of the tail tube and so no blow is imparted to that tube.

This blow not only accelerates the projectile but also forces the part 74 into the part 76 and the resultant expansion of the latter presses a flange 78 on the casing 66 into contact with the bore of the tube 62. As the gas check is moving

forward, some of the gases produced by firing the primary charge enter the spigot 58 and force a firing pin 80 through its forward end. When the spigot hits the casing 66 this pin fires the primer 68 and hence a secondary charge 82 within the strut parts 74 and 76.

Although in these examples all the propellant thrust is imparted to the projectiles by the explosion of the primary and secondary charge, the invention is equally applicable to projectiles which after discharge from the barrel of a weapon are assisted in flight by the combustion of an additional rocket charge.

I claim:

- 15 1. In a projectile having a head, a tail and a tube connecting said head and tail the combination of a gas check behind said tail, a strut within said tube adapted to transmit thrust from said gas check to said head, and means, including an explosive charge, within said tube for jettisoning said gas check and strut from said projectile.
- 20 2. A combination as claimed in claim 1 wherein a spigot rigid with said gas check enters said tube and forms a part of said strut.
- 25 3. A combination as claimed in claim 2 wherein means are provided for initially locating said spigot with a space between the end thereof and the remainder of said strut.
- 30 4. In a projectile having a head, a tail and a tube connecting said head and tail the combination of a gas check behind said tail, a strut within said tube adapted to transmit thrust from said gas check to said head, and means within said tube for jettisoning said gas check and strut from said projectile, said means including an explosive charge, a primer, a movable member exposed to gas pressure acting on said gas check, and a firing pin carried by said movable member and co-operating with said primer.
- 35 5. A combination as claimed in claim 1 and a primary explosive charge for discharging said projectile from a barrelled weapon, the proportion between said primary explosive charge and said explosive charge for jettisoning said gas check being such that immediately after being jettisoned said gas check has a velocity towards said weapon.
- 40 6. A combination as claimed in claim 5 wherein said proportion is such that said velocity of said gas check towards said weapon is greater than the velocity of said projectile on leaving said weapon.
- 45 7. A projectile having a head, a tail, a tube connecting said head and tail, a gas check behind said tail, strut means within said tube adapted to transmit thrust from said gas check to said head, and an explosive charge within said tube adapted to jettison said gas check and strut means from the projectile in flight.
- 50 8. LATHAM VALENTINE STEWART BLACKER.
